[57] CLAIM

The ornamental design for a horse blanket, as shown and described.

DESCRIPTION

FIG. 1 is a top plan view of a horse blanket showing my design;

FIG. 2 is a bottom plan view thereof; and,
FIG. 3 is a perspective view thereof in use.The dashed lines in FIG. 1 and 2 represent lines of stitching,
and the portions of FIG. 3 shown in broken lines form no
part of the claimed design.
